The ornamental design for a Saturn-shaped block holder as shown and described.

DESCRIPTION

FIG. 1 is a perspective view of a Saturn-shaped block holder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front elevational view thereof, shown in an environmental state of use.

The oblique shade lines in FIGS. 1 to 3 and 6 to 8 illustrate transparency/translucency of the disc on which they are shown.

The dash-dash broken lines showing a block in FIG. 8 represent environmental structure. The dash-dash broken lines connecting the broken line block to the block holder in FIG. 8 show alignment. The dot-dash broken lines represent a boundary line and denote the bounds of the claim. All other broken lines illustrate portions of the Saturn-shaped blocker holder. The broken lines form no part of the design.
